EDWIN E. CARLSON AND LAWRENCE A. STEAD, OF CHESTER, PENNSYLVANIA.

APPARATUS FOR PREPARING WARP YARN FOR DYEING.

Application filed May 17, 1927. Serial No. 191,958.

Our invention relates to warp dyeing and more particularly to means for dyeing an entire warp a uniform color throughout by immersing it in a dye bath.

5 A standard warp is 6,000 yards long and consists of 378 strands of yarn. These warps are usually dyed by passing them through a dye bath and squeezing out the excess dye liquor as they leave the bath. 10 Due to the affinity of the dye chemicals in the bath for the material in the yarn, the strength of the liquor is gradually diminished with the result that the first part of a warp passed through the bath is dyed a 15 deeper shade than is the last part. This variation in shade is not a serious defect in yarn to be used for some purposes, while for other purposes, notably for the production of knitted fabrics, the color of the yarn 20 must be uniform throughout.

When it is desired to produce a uniformly dyed warp, the usual method is to wind it into skeins, hang the skeins onto poles, insert the poles in a suitable rack, and immerse 25 same in a dye bath. This requires the unnecessary operations of reeling the warp into skeins and winding the warp from the skeins as well as requiring considerable hand labor in hanging the skeins onto poles and inserting 30 the poles in a rack.

The object of our invention is to provide apparatus that will plait an entire warp onto a rack so that it may be dyed in open form, without tension, and given a uniform 35 color throughout.

The drawings illustrate an embodiment of the invention and the views therein are as follows:

Figure 1 is a side elevation of an apparatus 40 adapted for carrying our invention into effect,

Figure 2 a view similar to Figure 1 but shown partly in section and having certain parts omitted.

Figure 3 is a front view, drawn to a larger scale, of the plaiting mechanism shown in Figure 1,

Figure 4 a fragmentary sectional view, partly in full and drawn to a still larger

scale, taken substantially on line 4—4 on 50 Figure 3, and

Figure 5 a fragmentary sectional view on line 5—5 on Figure 3.

The apparatus for plaiting the warp onto a suitable rack may be made in a variety of 55 forms but, for the purpose of illustration, we have shown in the accompanying drawings an apparatus adapted to assist in carrying our invention into effect and which may be either supported in a suitable frame 60 mounted on the floor or suspended from the ceiling by hangers 10 and 10^a. A driving shaft 11, having a pulley 12 keyed to one of its ends, is rotatably mounted in hangers 10 and provided with a keyway 13 extending the greater part of its length. A clutch part 14, having a chain sprocket 15 fixed thereto, is rotatably mounted on one end of shaft 11 and a similar clutch part 14^a rotatably mounted on the other end of shaft 65 70 11 and having a chain sprocket 15^a fixed to it. A clutch part 16 is slidably keyed on shaft 11 and adapted to engage clutch part 14 while a clutch part 16^a is adapted to engage clutch part 14^a. 75

A clutch part 14 and a clutch part 16 comprise an entire clutch of any conventional type which is adapted to act quickly but smoothly and with a very small amount of movement on the part of clutch part 16. 80 Any well known type of clutch which can be operated with a comparatively small throw would be applicable but it has been necessary to show clutch part 16^a separated a considerable distance from clutch part 14^a in order to plainly illustrate the operation of the apparatus, while, in reality, the movement of clutch part 16^a would be so slight that its change in position could not be illustrated in the drawing. 85 90

A shaft 17, threaded the greater part of its length, is rotatably mounted in hangers 16 and carries sprocket wheels 18 and 18^a near its ends. A chain 19 connects sprocket wheel 15 with sprocket wheel 18. A sprocket wheel 15^a is mounted on a stud shaft projecting from the frame and carries a gear 15^b 95 which meshes with a gear 11^a fixed to shaft

11. A chain 19^a connects sprocket wheels 15^a and 18^a. When clutch parts 14 and 16 are in engagement, and shaft 11 in rotation, sprocket wheel 15 will drive sprocket wheel 18 and actuate shaft 17 in one direction. When clutch parts 14^a and 16^a are thrown into engagement, gear 15^b is thrown into mesh with gear 11^a and shaft 17 is rotated in reverse directions.
- 10 A top rail 20 connects hangers 10 and provides a runway for a pair of wheels 21 which are journaled in an auxiliary frame 22 while a bottom rail 23 connects the lower ends of hangers 10 and extends through 15 suitable bearings 24 formed near the lower part of auxiliary frame 22. Screw bearings 25 are formed in each side of auxiliary frame 22 and screw shaft 17 threaded therethrough so that, as this shaft is rotated in one 20 direction, auxiliary frame 22 will be moved toward hanger 10, and when shaft 17 is rotated in the opposite direction, it will be moved toward hanger 10^a; wheels 21 supporting the frame and guiding its upper end 25 while the lower end of this frame slides on bottom rail 23.

As auxiliary frame 22 approaches clutch part 16, a contact 26, secured to one side of frame 22 will engage a stop 27, fixed on a rod 30 having each end hinged to a clutch lever 29 pivoted in brackets 30 secured to hangers 10, and move clutch part 16 out of engagement with clutch part 14 and simultaneously move clutch part 16^a into engagement with 35 clutch part 14^a and thus reverse the movement of frame 22. As auxiliary frame 22 approaches clutch part 16^a a contact 31, secured to the other side of auxiliary frame 22, engages a stop 27^a, causes clutch part 16 to 40 engage clutch part 14 and clutch part 16^a to disengage clutch part 14^a and again reverses the movement of frame 22.

A pinion 32, slidably keyed on shaft 11, is held between a bearing 33 and one side 45 of auxiliary frame 22 and meshes with a gear 34 fixed on a shaft 35 rotatable in auxiliary frame 22. A gear 36, fixed on a shaft 37 rotatable in auxiliary frame 22, meshes with gear 34 and with a gear 38 fixed on a shaft 50 39 rotatable in auxiliary frame 22. A roller 40 is fixed on shaft 35, a roller 41 on shaft 37, and a roller 42 on shaft 39 and these rollers are adapted to feed the warp through the apparatus as will hereinafter be described.

A brace 43 extends across auxiliary frame 22 and has a socket 44 formed near its center which is adapted to support a plaiting tube 45 in such a manner that it may rock in 55 socket 44. A pinion 46 is secured to shaft 39 and meshes with a gear 47 journaled on a stub shaft 48 fixed to one side of auxiliary frame 22. A link 49 is provided in one end with a slot 50, which straddles a pin 51 fixed 60 to the side of gear 47, and has its lower end

keyed to a shaft 52 rotatable in the lower ends of auxiliary frame 22 and having a lever 53 keyed thereto in line with plaiting tube 45; the lower end of lever 53 being hinged to a strut 54 which is rigidly connected to the lower end of the plaiting tube. 70

It will thus be evident that, as gear 47 rotates, pin 51 will move along slot 50 and oscillate the upper end of link 49, rock shaft 52 and consequently oscillate the lower ends of lever 53 and plaiting tube 45. It will also be evident that, as pin 51 and stub shaft 48 come into horizontal alignment with one another, the movement of the lower end of plaiting tube 45 will cease and that its speed will increase as pin 51 leaves these two points and approaches its uppermost or lowermost position when it will be in alignment with shafts 48 and 52 and the lower end of plaiting tube 45 be moving at its maximum speed. The apparatus is so designed that the end of plaiting tube 45 will be immediately above one of the poles 55, forming a part of a rack 56, when pin 51 and shafts 48 and 52 are in alignment and the end of the tube comes into close proximity with an adjacent pole 55 at each end of its swing, as shown in dot-and-dash lines on Figure 2. 80

A warp 57 is led from the original package over roller 40, rearwardly and around roller 41, and over roller 42 into plaiting tube 45. The mechanism is so timed that the rollers will feed a double length of warp between two poles 55 while gear 47 is causing the end of tube 45 to traverse the space between these two poles. Thus, as gear 47 makes a half revolution, the rollers will feed a length of warp extending from the top of a pole 55 downwardly the desired distance and upwardly to the top of the pole again; the tube 100 is then caused to pass over the top of the pole 55 by continued rotation of gear 47 and the same operation is repeated on the opposite side of this pole during the second half revolution of gear 47. As the loops of warp usually extend 27 inches below poles 55, 54 inches of warp is fed through tube 45 while it is moving over the space between two of the holes. 105

As screw shaft 17 is being rotated constantly, auxiliary frame 22 will move longitudinally of the pole 55 on which the warp is being plaited and stops 27 are so adjusted that contacts 26 or 31 will engage them and reverse the movement of screw shaft 17 when plaiting tube 45 arrives at the end of a pole 55. Screw shaft 17 is rotated at such a speed that the strands of warp lying across the top of poles 55 are spaced one against the other so that each pole is completely filled with warp. 115

Rack 56 is supported in a carriage 58 during the plaiting process and this carriage is preferably supported on a suitable track 59 and adapted to be moved along by means of 120 130

a chain 60 carried on sprockets 61 and 61^a rotatably mounted in bearings 62. Sprocket 61 has a ratchet wheel 63 fixed thereto and adapted to be engaged by a pawl 64 pivoted 5 on an arm 65 and held in engagement with the ratchet wheel by a spring 66 in the well known manner.

A rod 67 has one end secured to the outer end of arm 65 and its other end secured to 10 one arm of a bell crank 68 pivoted in the lower end of hanger 10. The other arm of bell crank 68 is provided with an extension 69 adapted to be contacted by the end of shaft 52 just before contact 26 engages stop 15 27 so that rod 67 is moved upwardly and causes arm 65 and pawl 64 to rotate ratchet wheel 63 two notches; the relative size of sprocket 61 to ratchet wheel 63 being such that rotation of the ratchet wheel two 20 notches will cause sprocket 61 to move chain 60 a distance equal to the distance between the centers of two poles 55 in rack 56.

Carriage 58 may be connected to chain 60 in any suitable manner as by having a 25 projection 70 formed on one end and engaged by a block 71 secured to chain 60 or chain 60 may be provided with a plurality of blocks 71, which are so designed that they are adapted to pass around sprockets 61, or it 30 may be provided with a single connection to carriage 58 and the carriage returned to its starting position by merely lifting pawl 64 out of engagement with ratchet wheel 63 and pushing the carriage rearwardly.

35 In order that carriage 58 may be fed forwardly one space when auxiliary frame 22 approaches the opposite end of shaft 17, we hinge a bell crank 72 in the lower end of hanger 10^a and connect the upper arm of 40 this bell crank to the lower arm of bell crank 68 by means of a link 73. An extension 69^a is formed on the lower arm of bell crank 72 and is adapted to be abutted by the end of rod 52 just before contact 31 engages stop 27 45 so that carriage 58 may be fed forwardly just before the direction of rotation of shaft 17 is changed. The weight of rod 67 should be sufficient to more than counterbalance bell cranks 68 and 72 and link 73 so that pawl 50 64 may be returned to its normal position by the force of gravity and prevented from dropping below this position by bell crank 68 abutting a step 74 formed in the bifurcated end of hanger 10.

55 Racks 56 are preferably of such size that they will just nicely accommodate an entire warp. When rack 56 has been filled, carriage 58 is in a position in advance of the plaiting mechanism so that rack 56 may be lifted by 60 a suitable hoist and placed in a dyeing vat. Carriage 58 may then be returned to its starting position and another rack 56 placed therein and filled while the warp on the first rack is being dyed.

65 The dyeing vat has not been illustrated as

it may be of the well known Hussong type which is ordinarily employed for dyeing yarn in skein form. In this instance, however, the yarn carrying poles are not rotated as this would tangle the yarn. The dye 70 liquor is circulated in the usual manner and should preferably, for at least a portion of the time, pass upwardly through the yarn compartment so as to float the yarn free of the poles and allow it to become thoroughly 75 saturated.

In dyeing warp yarn according to our method, the end of the warp is led from the original package over and around rollers 40, 41 and 42, as previously described, and 80 lapped over the end pole 55 in rack 56; carriage 58 having been previously placed in position. Plaiting tube 45 will oscillate to deposit a loop first on one side of the pole and then on the other while auxiliary frame 22 is fed 85 longitudinally, relatively to pole 55, by the action of screw shaft 17 until this pole is covered by adjacently disposed loops of warp.

Carriage 58 will then be fed forwardly to 90 bring the next pole in position and screw shaft 17 will be reversed so that auxiliary frame 22 is fed in the opposite direction and plaiting tube 45 directs warp over the length of this pole. This process continues until 95 the entire warp has been disposed on the poles in rack 56 which is then removed from carriage 58 and placed in the dyeing vat and dyed in the usual manner as noted above. Carriage 58 is then provided with an empty 100 rack and returned to the starting position so that this rack may be filled as above described.

In order that the plaiting mechanism will not continue to feed warp after a rack has 105 been filled, we preferably provide means for stopping this mechanism. A number of ways to accomplish this result will readily suggest themselves to any mechanic and different devices may be required for different 110 situations. In the present application of our invention, we attach a contactor 75 to the rear end of carriage 58 so that its lower end extends downwardly between the rails of track 59. We place an electric switch, 115 normally held closed by a spring and electrically connected to the motor which operates the plaiting mechanism, below the rails near bearings 62. After the last pole in rack 56 has been filled, carriage 58 will 120 be fed forwardly one more space in the usual manner and cause contactor 75 to open the switch and deprive the motor of its power. It is evident that a switch opener may be secured to other parts of the carriage or in 125 any other suitable place, as on chain 60.

If shaft 11 is belt driven from a line shaft, a clutch may be installed which is adapted to be operated by a lever arm attached to a vertical shaft having a lever arm on its lower 130

end adapted to be engaged by a contactor attached to carriage 58 or to the carriage moving mechanism. Other means may be employed and different installations will probably require different stopping means. As a skilled mechanic can readily provide such means to meet the requirements of a specific installation, none of these means have been illustrated in the drawings.

- 10 10 By the use of our invention and following our improved method, it is not necessary to reel the yarn into skeins, unwind it from the skeins, place the skeins on the poles by hand or remove the skeins from the poles, thus affording a great saving in time, labor and overhead expense while producing an evenly dyed product.

It is evident that the apparatus for preparing warp yarn for dyeing illustrated 20 herein is susceptible of various changes and modifications without departing from the invention herein set forth and hereafter claimed.

We claim:

- 25 1. In apparatus of the character described, a rack, poles spaced in the rack, means for supporting the rack, and means for plaiting yarn onto the poles.

2. In apparatus of the character described, 30 a carriage, a rack on the carriage, poles spaced in the rack, means for plaiting yarn onto the poles, and means for moving the carriage.

3. In apparatus of the character described, 35 a carriage, a rack on the carriage, poles spaced in the rack, means for plaiting yarn onto the poles, means for moving the carriage, and means adapted to interrupt the flow of yarn from the plaiting means.

- 40 4. In apparatus of the character described, a carriage, a rack on the carriage, poles spaced in the rack, means for plaiting yarn over a pole, means for moving the plaiting means longitudinally of the pole, means for moving the carriage to bring succeeding poles into position to be filled with 45 yarn, and means for interrupting the flow of yarn from the plaiting means when a predetermined length of yarn has been fed therethrough.

- 50 5. Yarn plaiting mechanism including a frame, a plaiting tube oscillatable in the frame, means for feeding yarn through the plaiting tube, a screw shaft for feeding the plaiting tube transversely of the frame, means for rotating the screw shaft, and means for changing the direction of rotation of the screw shaft.

- 60 6. Yarn plaiting mechanism including a main frame, an auxiliary frame carried by the main frame, a plaiting tube oscillatable in the auxiliary frame, rollers in the auxiliary frame for feeding yarn through the plaiting tube, a screw shaft threaded in the auxiliary frame and rotatable in the main frame,

and means for rotating the screw shaft alternately in opposite directions.

7. Yarn plaiting mechanism including a main frame, an auxiliary frame carried by the main frame, a plaiting tube oscillatable 70 in the auxiliary frame, means for feeding yarn through the plaiting tube, a main shaft rotatable in the main frame, a screw shaft threaded in the auxiliary frame and rotatable in the main frame, clutch sprockets rotatable on the main shaft and mechanically connected to the screw shaft, and clutch parts slidably keyed to the main shaft and adapted to selectively engage the clutch sprockets. 75

8. Yarn plaiting mechanism including a main frame, an auxiliary frame carried by the main frame, a plaiting tube oscillatable in the auxiliary frame, means for feeding yarn through the plaiting tube, a main shaft 80 rotatable in the main frame, a screw shaft threaded in the auxiliary frame and rotatable in the main frame, clutch sprockets rotatable on the main shaft and mechanically connected to the screw shaft, clutch parts slidably keyed to the main shaft, clutch levers engaging the clutch parts, a rod connecting the clutch levers, and stops on the rod adapted to be abutted by the auxiliary frame for causing one clutch part to engage and the other disengage its clutch sprocket. 85

9. In yarn plaiting mechanism having a main frame, an auxiliary frame carried by the main frame and a plaiting tube hung in the auxiliary frame; means for oscillating the plaiting tube including a shaft rotatable 100 in the auxiliary frame; a strut fixed to the plaiting tube; a lever hinged to the strut and fixed to the shaft; a link fixed to the shaft and having an elongated slot; a wheel rotatable in the auxiliary frame; a pin in the wheel and extending through the slot; and means for rotating the wheel. 105

10. In a yarn plaiting apparatus including yarn plaiting mechanism, having a main frame and an auxiliary frame, and a yarn receiving carriage; means for intermittently moving the carriage including a track for guiding the carriage; sprocket wheels rotatable adjacent the track; a chain carried by the sprocket wheels; means connecting the carriage to the chain; a ratchet fixed to rotate with one of the sprocket wheels; a pawl engaging the ratchet and mechanically connected to the plaiting mechanism, whereby operation of said mechanism will intermittently cause the pawl to impart rotary movement to the ratchet wheel. 110

11. In a yarn plaiting apparatus including 115 yarn plaiting mechanism, having a main frame and an auxiliary frame movable transversely of the main frame, and a yarn receiving carriage; means for intermittently moving the carriage including a track for guiding the carriage; sprocket wheels rotat- 120

able adjacent the track; a chain carried by the sprocket wheels; means connecting the carriage to the chain; a ratchet fixed to rotate with one of the sprocket wheels; an arm 5 rockably mounted adjacent the ratchet wheel; a pawl hinged on the arm and engaging the ratchet wheel; a bell crank hinged on the main frame; a rod connecting the arm and the bell crank; and means adapting the auxiliary frame to actuate the 10 bell crank and cause the pawl to impart rotary movement to the ratchet wheel.

In testimony whereof we have signed our names to this specification.

LAWRENCE A. STEAD.
EDWIN E. CARLSON.
